UNITED STATES PATENT OFFICE.

PAUL PAVLIK, OF NEW YORK, N. Y.

MACHINE FOR MAKING BUTTONS.

1,101,144.

Specification of Letters Patent. Patented June 23, 1914.

Application filed June 10, 1912. Serial No. 702,684.

To all whom it may concern:

Be it known that I, PAUL PAVLIK, a subject of the King of Hungary, and a resident of the borough of Manhattan, in the city, county, and State of New York, having declared my intention of becoming a citizen of the United States, have invented certain new and useful Improvements in Machines for Making Buttons, of which the following 10 is a specification.

The object of my invention is to afford an apparatus in which the operations of drilling thread holes and forming fish-eyes may be simultaneously performed on button 15 blanks fed into, and presented for cutting, in a duplex holder or chuck head which is turned and advanced and retracted intermittently by automatic means, as herein-after set forth.

20 The invention also includes certain other features in the specific construction and arrangement of parts described and claimed.

In the accompanying drawings, Figure 1, is a plan of my improved apparatus, broken 25 away in parts; Fig. 2, a side elevation of the same, also partly broken away; Fig. 3, is an end elevation; Fig. 4, is a side elevation of the blank forwarding and retracting mechanism with the blank holder advanced; Fig. 5, is a sectional elevation showing the 30 blank holder retracted; Fig. 6, is a sectional elevation of the parts in the position shown in Fig. 4; Fig. 6^a, is a detail view of the chuck holder detent; Fig. 6^b, is a detail view 35 of the rear deflector; Fig. 7, shows a front view of the blank holder, &c.; Fig. 8, is a sectional elevation taken upon plane of line 8—8, Fig. 1, but on a larger scale; Fig. 9, is a sectional elevation of the fish-eye cutter; Fig. 10, a sectional elevation upon plane of line 40 10—10, Fig. 9; Fig. 11, a central longitudinal sectional elevation of the thread hole drilling mechanism, partly broken away; Fig. 12, is a sectional elevation upon plane 45 of line 12—12, Fig. 11; Fig. 13, is a view illustrating the use of a hand lever for effecting the reciprocation of the feed spindle, &c.; Fig. 14, is a sectional elevation taken upon plane of line 14—14, Fig. 4, looking 50 toward the rear of the cross head; Fig. 15, is a front view of one of the drill chucks.

B, represents the bed of the apparatus upon which the parts are mounted in proper 55 relation to each other.

The apparatus as a whole comprises three

devices which coöperate in unison in attaining the result desired, namely, the simultaneous treatment of two button blanks whereby one is pierced to form the thread holes, 60 and the other grooved to form the "fish-eye."

F, is the feed mechanism; D, the thread hole drilling mechanism extending in longitudinal alinement therewith, and E, the fish-eye cutting mechanism extending at right 65 angles to the other two. The hole drilling device, and the fish-eye cutter are positioned stationary with relation to each other and to the feed mechanism F, which presents the blanks successively to the other two, and 70 hence is reciprocatory in character.

The blank holder H, consists essentially of a cross head upon which are mounted two chucks h, in axial parallelism with each other and with the longitudinal axis of the 75 spindle a, upon which the cross head H, is rigidly mounted. Each chuck h, is formed with expanding jaws which are contracted when seated in the cross head, in which position they are held normally by springs h', 80 interposed between the cross head and a collar h², on the shank of the chuck, the rear extremity of which shank protrudes at the back of the cross head to form a contact h³, for engagement with the releasing stop r, 85 under conditions hereinafter described. An intermittent reciprocal and rotary motion is imparted to the spindle a, by suitable mechanical expedients. Thus in the contrivance shown in the drawings a rock lever 90 c, is used to reciprocate the spindle a, and the latter is caused to make a quarter turn upon its longitudinal axis at each advance and retraction of the spindle by means of cams a', a'', thereon contacting with stationary deflectors f, f', with the result that the cross head H, is correspondingly rotated one quarter of a circle, so that each chuck h, 95 temporarily and successively assumes four positions during each revolution of the spindle a.

The rock lever c, is fulcrumed on a bridge bracket b, between the standard b', b', extending upward from the common base B, said standard being formed with the bearings b², b², supporting the spindle a, and with the brackets b³, b³, upon which the stationary deflectors f, f', are mounted, and also with the bracket b⁴, upon which the stationary detent f'', is mounted. The lever is 105 of the second order, the work being between the fulcrum and the power, and hence is 110

formed with an annular yoke c' , carrying pins c^2, c^3 , engaging with holes formed for their reception in the sleeve a^2 , upon the spindle a , as will be seen more particularly by reference to Fig. 8, in which it will also be seen that the lever c , is fulcrumed on the bridge bracket b , in such manner as to admit of a slight degree of play to compensate for the movement of the spindle a , upon its longitudinal axis.

The sleeve a^2 , being loose upon the spindle a , except as held against rotation therewith by the pins c^2 , of the yoke c' , is confined between shoulders a^3, a^3 , on said spindle, the shoulders a^3, a^3 , in the present case consisting of the abutting ends of the cam sleeves a', a'' , which latter are rigidly secured to the spindle a . The lever c , is rocked to effect the reciprocation of the spindle longitudinally, either manually by means of a handle c^3 , pivotally connected therewith as shown in Fig. 13, or automatically by means of a cam and connections as shown in Figs. 1 and 2 of the drawings, in which G represents a disk cam on one end of a transverse shaft g , mounted in bearings on the standard b^5 , upon the base B , the other end of said transverse shaft g , carrying a miter gear g' , which meshes with a pinion g^2 , on the driving shaft g^3 , also mounted in bearings on the standard b , and provided with the driving pulley g^4 , as shown in Fig. 1.

The face of cam G , is formed with the thrust groove g^5 , into which protrudes a roller g^6 , (shown in dotted lines in Fig. 1,) mounted upon the slide g^7 , supported in guides b^6, b^6 , on the standard b^5 . The slide g^7 , is pivotally connected with the rock lever c , by a coupling link L , which is adjustable in length to regulate the relation of the parts with accuracy, and particularly with relation to the forward thrust of the spindle a , for the purpose of governing the depth of the fish-eye cut in the blanks by fish-eye cutting mechanism. The concentric portion 1, of the thrust groove g^5 , represents the period when the spindle a , and cross head H , are advanced and presenting the button blanks to the action of the hole-drilling and fish-eye cutting mechanism, while the concentric portion 2, of said groove g^5 , represented the retracted position of the spindle a , and head H , during which period a finished blank is discharged and a fresh blank substituted therefor, as hereinafter more fully set forth. The intermediate or eccentric portions 3, 3, of the groove g^5 , represent the forward and retractile thrusts of the spindle a , as imparted thereto through the medium of the slide g^7 , link L , rock lever c , and sleeve a^2 .

The cam sleeves a', a'' , are each formed with diametrically opposed cam surfaces 4, 4, and with recesses 5, 5, and the cam surfaces 65 and recesses on one cam sleeve break joints

or are intermediate with relation to those on the other cam sleeve. Likewise the cam surfaces project outward in opposite directions and away from the intermediate sleeve a^2 , which latter is not secured to the spindle a , in such manner as to rotate therewith, whereas the cam sleeves a', a'' , are rigidly attached to the spindle. As a result, as the spindle a , is moved by the actuating sleeve a^2 , in either direction either one or the other of the cam surfaces 4, will encounter one or the other of the stationary deflectors f, f' , causing the spindle to rotate upon its longitudinal axis until the said deflector enters the recess 5, on that side of the spindle, thereby holding the spindle against further rotation until it is moved longitudinally in the opposite direction, when the operation is repeated on the other side of the actuating sleeve a^2 , the spindle making a quarter turn at each longitudinal thrust, of which there are thus four to each complete revolution of the spindle.

The spindle a , is shown at the end of the forward or working thrust in Figs 1, 2, 4 and 6, and at the end of the retractile thrust in Fig. 5. When the spindle is retracted the cross head H , is always in a horizontal position whereas when the spindle is advanced the head is always in a vertical position although reversed alternately at each half revolution of the spindle. Thus obviously the chucks h , alternate in position, not only as related to the drilling and grooving tools, but also as related to the releasing trip r , which may consist of the head of a screw engaging with a threaded boss b^7 , on one side of the standard b^5 , a lock nut r' , being used to set the adjustment so that when the spindle is retracted the inner end contact h^3 , of one of the clutches h , will impinge against said stop r , unseating the clutch jaws against the resistance of the spring h' , and allowing the jaws to expand and release the button. The outer concentric portion 2, of the cam groove g^5 , is timed to allow of this release and the insertion of another blank in lieu of the one discharged before the beginning of the advance movement of the spindle a , upon which advance the removal of the contact h^3 , from the stop r , allows the spring h' , to re-seat the clutch jaws and clamp the new blank in position for presentation first to the fish-eye cutter c , and then to the drills d, d .

The cross head h , is held in the advanced vertical position, not only by reason of the engagement of the forward deflector f , with a recess 5, in the forward cam sleeve a' , but also by a detent f'' , on the bracket b^4 , which enters a notch h^4 , one of which is formed in each end of the cross head at the rear side thereof as shown in Fig. 14. Thus the cross head is centralized and supported laterally during the operation of the cutters.

The fish-eye cutter e , is secured to the end of a rotatable spindle i , mounted in bearings i' , i'' , on a carriage I , which is adjustable laterally on the bed B , for the purpose of regulating the position of the cutter e , with relation to the advanced position of the under chuck h , in the cross head H , thereby gaging the depth of the fish-eye groove formed in the button blank. The carriage 5 I , rests between parallel ways b^x , b^x , on the base B , which preserve its longitudinal alinement at right angles to the feed mechanism F , and drilling mechanism D . It is clamped to the bed B , by a bolt b^s , passing 10 through a transverse slot i^{22} , in the floor of the carriage I , (see Figs. 9 and 10) said slot affording ample lateral adjustment for the fish-eye cutter e . This lateral adjustment of the spindle i , and fish-eye cutter e , is primarily intended to compensate for differences 15 in the diameters of the cutters e , which may be used. The accurate adjustment of depth of fish-eye cut is effected through the medium of the link L , by means of which the forward thrust of the spindle may be regulated so as to present more or less of the thickness of the blank in the upper chuck h , to the action of the cutter e . When the spindle a , is reciprocated manually, as 20 by a hand lever c^s , as indicated in Fig. 13, the forward thrust of the spindle is limited and regulated by an adjustable stop r^2 , which may consist of a set screw engaging the threaded boss b^r , and secured in the prescribed 25 position by a lock nut r^3 , as shown in said Fig. 13,—a bearing c^{33} , on the lever c^s , (or on the rock lever c , if preferred) contacting with said stop r^2 , to limit the degree of penetration of the fish-eye cutter e , into the button blank as before mentioned. 30 This regulation of the depth of the fish-eye groove by the adjustment of the cutter in button machinery enables me to produce buttons having fish-eyes of uniform depth and appearance. 45

The longitudinal adjustment of the spindle i , in its bearings i' , i'' , is effected by a bearing screw i^2 , engaging a thread formed in a bracket arm i^3 , at the rear of the carriage I , said set screw i^2 , being provided with a jam nut i^4 , to lock it in the prescribed position. The end of the set screw i^2 , impinges against a hardened bearing i^5 , (Fig. 9) inserted in the end of the spindle, 50 and constitutes a back rest therefor. The spindle is held against longitudinal movement in the opposite direction by a collar i^6 , resting against the inner side of the front bearing i' , said collar i^6 , forming part of a sleeve i^7 , on which is a coiled spring i^8 , interposed between the collar i^6 , and the pulley i^9 . The collar i^6 , is secured to the spindle i , by a set screw i^{10} , and the pulley i^9 , by a set screw i^{11} . When it is desired to effect the longitudinal adjustment of the spindle

i , the set screw i^{10} , is loosened, and the bearing screw i^2 , advanced or retracted as desired, the spring i^8 , holding the collar i^6 , against the bearing i' , but permitting and compensating for the longitudinal movement of the spindle i . When the desired adjustment is effected the set screw i^{10} , is again tightened, thereby again locking the spindle against longitudinal movement in either direction. The bearings i' , i'' , are 70 provided with the usual bushings, and means for lubrication; and the spindle is rotated by a belt applied to the pulley i^9 . The hole drilling device D , as before stated, is in alinement vertically with the longitudinal axis of the feed mechanism, the drills d , being focused toward the center of the upper chuck h , when the cross head H , is in the vertical position so that when the spindle a , is advanced, the button blank 80 in said upper chuck will be pierced with the requisite thread holes. The drills, as heretofore, are steel wires, chisel-sharpened at their cutting ends, their opposite extremities or shanks being inserted and 85 clamped in chuck jaws d' , d' , on rotatable spindles d^2 , d^2 . These spindles d^2 , d^2 , consist each of an outer tube d^3 , mounted in bearings in standards b^9 , b^{10} , on a frame b^{11} , attached to the base B . Each outer tube 90 d^3 , is provided with a driving pulley d^4 , and a collar d^5 , the hub of the pulley and the collar d^5 , abutting against the rear standard b^9 , and holding the spindle against longitudinal movement. The forward end of 95 each outer tube d^3 , is flared or beveled outward to contact with conoidal chuck jaws d' , and close them when the inner tubes d^6 , (of which the jaws d' , form a part) is drawn inward by means of the hand nut d^7 , 100 which engages the threaded rear end of said inner or clutch tube d^6 . The drill spindles d^2 , are driven by preference by means of a belt common to all contacting with the several pulleys d^4 . It will 110 be seen that the drill spindles converge so that the drills d , are concentrated, their outer ends being supported in a perforated bushing d^8 , mounted in the forward bracket arm b^{12} , on the standard b^{10} , of the frame b^{11} . 115 The drill point supporting bushing d^8 , is detachable, being held in place by a set screw d^9 ; and different point supporting bushings d^8 , are used according to the desired relative arrangement and number of the holes to be 120 drilled in the button blank. An adjustable intermediate support d^{10} , is provided for the drills between the point supporting bushings d^8 , and the chucks d' , said intermediate support being provided with a perforated bushing d^{11} , through which the drills extend, and with a threaded shank d^{12} , extending through a longitudinal slot b^{13} , in the forward bracket arm b^{12} , and held in place by a thumb nut d^{13} . This intermediate support 125 130

d^{10} , not only guides and sustains the drill wires, preventing their sagging, but it also performs the function of a spreader or spacer to compensate for differences in the 5 point-bushings d^8 , used on the forward end of the bracket b^{12} .

By my construction and arrangement of parts the drills d , may be quickly and conveniently inserted or withdrawn from the 10 chucks d' , when the cross head H , is in the horizontal position without unshipping or disturbing any of the parts,—it being then simply necessary to open or close the jaws d' , by means of the hand nuts d^7 , at the rear of 15 the spindles d^2 . Furthermore the hollow construction of the latter admits of the use of long drill wires which may be sharpened many times before they are too short for use; and it also facilitates the insertion and 20 adjustment of the drill into position for use.

The operation of the apparatus is as follows. The parts being in the positions shown in Figs. 1 and 2 with the cross head H , thrust forward and in vertical position 25 (see also Figs. 4, 6 and 7) the rotation of the cam G , causes the roller g^6 , to enter one of the eccentric portions 3, of the cam groove g^5 , retracting the slide g^7 , and through the coupling link L , rocking the lever c . This 30 causes the sleeve a^2 , to retract the spindle a , withdrawing the forward cam sleeve a' , from the forward stationary deflector f , and the lower notch h^4 , in the cross head away from the detent f'' , and also bringing the 35 cam surface of the rear cam sleeve a'' , into contact with the other stationary deflector f' , on the rear bracket b^3 . As a result of this last named contact the deflector f' , enters a notch 5, in the cam sleeve a'' , at the completion 40 of a quarter revolution of the spindle a , upon its longitudinal axis, thereby bringing the cross head into the horizontal position, with the contact h^3 , of the chuck h , (carrying the button blank which has just been 45 drilled with thread holes) into engagement with the trip r , by which action the clutch jaws are unseated and expand to release the blank. While the roller g^6 , is in the outer concentric portion 2, of the cam G , a fresh 50 blank is substituted for that discharged, to be in turn clamped by the jaws under the action of the spring h' , when the contact h^3 , leaves the trip r , after the roller g^6 , encounters the other eccentric portion 3, of the 55 cam groove g^5 , thereby acting through the slide g^7 , link L , rock lever c , and sleeve a^2 , to forward the spindle a . During the forward movement of the spindle a , the rear cam sleeve a'' , clears the stationary deflector 60 f' , and the cam surface on the forward cam sleeve a' , encounters the forward deflector f , causing the spindle a , to again make a quarter revolution upon its longitudinal axis by the time said forward deflector f , has entered the recess 5, on that side of the cam 65

sleeve a' , and again returning the parts to the relative positions shown in Figs. 1, 2, 4, 6 and 7, except that the cross head has been reversed in position vertically, the chuck h , carrying the blank from the fish-eye cutter e , being now on top and said blank being presented to the drills d , for piercing, while the fresh blank is being subjected to the action of the fish-eye cutter e . As the cam-sleeves a' , a'' , are duplex in character 70 and each bi-laterally symmetrical, it is obvious that upon the next revolution of the cam G , the operation above described will be repeated, and so on continuously as long as fresh blanks are substituted for those discharged automatically as set forth. 75

Where it is desired to operate the feed manually the cam G , is dispensed with or the link L , disconnected from the rock lever c , and the hand lever c^3 , pivotally connected therewith as hereinbefore set forth. Otherwise the operation is the same as heretofore described, the hand lever c^3 , being a substitute for the cam slide g^7 . In either case the operation of the eye-cutting mechanism E , and of the hole drilling mechanism D , is the same and continuous,—the work, *i. e.*, the button blanks, being advanced and fed to the tools, which are relatively speaking stationary in position. At the same time the apparatus is adapted for special hand work when desired, where extra care and finish are requisite in the production of finer grades of goods. 80

What I claim as my invention and desire 100 to secure by Letters Patent is,

1. In apparatus of the character designated, the combination of horizontally disposed fish-eye cutting mechanism and thread-hole drilling mechanism positioned at right angles with relation to each other, and operative at different levels, a cross head, blank chucks mounted upon said cross head, a horizontal spindle on which said cross head is mounted, the longitudinal axis of said spindle being midway between the longitudinal axes of the said cutting and drilling mechanisms, means for turning and reciprocating said spindle, and means for opening said chuck alternately when the cross head is in the intermediate horizontal position, comprising cam surfaces upon the spindle, stationary deflectors with which said cams contact, a loose sleeve on said spindle, and a rock lever engaging said sleeve, whereby the reciprocation of the spindle causes its rotation, as and for the purpose set forth. 110

2. In apparatus of the character designated, the combination of horizontally disposed fish-eye cutting mechanism and thread-hole drilling mechanism positioned at right angles with relation to the other, and operative at different levels, a cross head, blank chucks mounted upon said cross head, a horizontal spindle on which said cross head is 125

- mounted, the longitudinal axis of said spindle being midway between the longitudinal axes of the said cutting and drilling mechanisms, means for turning and reciprocating 5 said spindle, means for opening said chucks alternately when the cross head is in the intermediate horizontal position, comprising oppositely disposed cams on said spindle, stationary deflectors with which said cams 10 contact, a loose sleeve on said spindle interposed between said cams, and a rock lever engaging said sleeve, whereby the reciprocation of the spindle causes its rotation, step by step, as and for the purpose set forth.
- 15 3. In apparatus of the character designated, the combination of horizontally disposed fish-eye cutting mechanism and thread-hole drilling mechanism positioned at right angles with relation to each other, and operative 20 at different levels, a cross head, blank chucks mounted upon said cross head, a horizontal spindle on which said cross head is mounted, the longitudinal axis of said spindle being midway between the longitudinal 25 axes of the said cutting and drilling mechanisms, means for turning and reciprocating said spindle, and means for opening said chucks alternately when the cross head is in the intermediate horizontal position, comprising 30 oppositely disposed cams on said spindle, stationary deflectors with which said cams contact, a loose sleeve on said spindle interposed between said cams, a rock lever 35 engaging said sleeve, a slide pivotally connected with said rock lever, an adjustable link interposed between said rock lever and said slide, and a cam arranged to automatically reciprocate said slide, as and for the purpose set forth.
- 40 4. In apparatus of the character designated, the combination of horizontally disposed fish-eye cutting mechanism and thread-hole drilling mechanism positioned at right 45 angles with relation to each other, and operative 50 at different levels, a cross head, blank chucks mounted upon said cross head, a horizontal spindle on which said cross head is mounted, the longitudinal axis of said spindle being midway between the longitudinal axes of the said cutting and drilling mechanisms, means for turning and reciprocating said spindle, and means for opening said chucks alternately when the cross head is in the intermediate horizontal position, comprising 55 oppositely disposed cams on said spindle, stationary deflectors with which said cams contact, a loose sleeve on said spindle interposed between said cams, a rock lever 60 engaging said sleeve, a slide pivotally connected with said rock lever, an adjustable link interposed between said rock lever and said slide, and a cam arranged to automatically reciprocate said slide, as and for the purpose set forth.
- 65 5. In apparatus of the character designated, the combination of the horizontally disposed fish-eye cutting mechanism and thread-hole drilling mechanism positioned at right angles to each other and operative 70 at different levels, a cross head formed with notches h^4 , h^4 , blank chucks mounted upon said cross head, a horizontal spindle upon 75 which said cross head is mounted, the longitudinal axis of said spindle being midway between the longitudinal axes of said cutting and drilling mechanisms, means for turning and reciprocating said spindle, and a stationary detent f'' , engaging the said notches h^4 , h^4 , in the cross head, as and for the purpose set forth.
